US00D556110S

(12) **United States Design Patent** (10) **Patent No.:** **US D556,110 S**
(45) **Date of Patent:** **** Nov. 27, 2007**

(54) **VEHICLE TAILGATE**

(75) Inventors: **Patrick Schiavone**, Bloomfield, MI (US); **Gordon Platto**, Troy, MI (US); **Michael Smith**, Plymouth, MI (US)

(73) Assignee: **Ford Global Technologies, LLC**, Dearborn, MI (US)

(**) Term: **14 Years**

(21) Appl. No.: **29/246,016**

(22) Filed: **Dec. 21, 2005**

(51) **LOC (8) Cl.** **12-16**

(52) **U.S. Cl.** **D12/196**

(58) **Field of Classification Search** D12/196, D12/98, 93; 296/57.1, 3, 26, 50, 37.1, 37.6

See application file for complete search history.
